UNITED STATES PATENT OFFICE.

ROBERT W. VAN BUREN, OF WHITE PLAINS, NEW YORK.

SUPPORT.

1,294,729.

Specification of Letters Patent. Patented Feb. 18, 1919.

Application filed January 4, 1918. Serial No. 210,303.

To all whom it may concern:

Be it known that I, ROBERT W. VAN BUREN, a citizen of the United States, residing at White Plains, in the county of Westchester and State of New York, have invented new and useful Improvements in Supports, of which the following is a specification.

This invention relates to improvements in supports and it is the principal object of the invention to provide a trouser hanger for receiving a plurality of pairs of trousers and supporting the same in a manner to retain the proper shape thereof.

Another and equally important object of the invention is to provide a trouser hanger capable of supporting a plurality of pairs of trousers in such a way as will permit the removal of any one pair without disturbing the others or causing wrinkling of the same.

Among other aims and objects of the invention may be recited, the provision of a device of the character mentioned with a view to compactness, and in which the number of parts are few, the construction simple, the cost of production small, and efficiency and operation high.

The foregoing together with additional advantageous details and arrangement of parts of the preferred embodiment of my invention will be clear from the specific description hereinafter contained, when read in connection with the accompanying drawings, forming part thereof, wherein said embodiment of the invention is illustrated for the purpose of facilitating a full understanding of the present improvements.

In the drawings:—

Figure 1 is a front elevation of the improved hanger,

Fig. 2 is a vertical transverse section therethrough,

Fig. 3 is a plan view of the device in blank, and

Fig. 4 is a detail in perspective of one of the clamping arms.

Referring now more particularly to the drawings and in connection with which like reference characters will designate corresponding parts throughout the several views, 1 represents the base or body portion of the improved hanger, the same being preferably formed of sheet metal, aluminium or the like and having a plurality of pairs of oppositely disposed bracket arms 2 formed integral

with the side marginal portions thereof, these bracket arms, obviously, being apertured as at 3 for a purpose which will be subsequently apparent. Portions of the base are cut away as at 4 to reduce the weight of 60 the construction and also to add to the attractiveness of the same, as well as provide means for permitting trousers to be engaged with the clamping arms hereinafter described. After the base or body portion has 65 been stamped or otherwise formed, the same is then bent so as to provide a plurality of stepped shoulders generally indicated by the numeral 5, thereby causing the various pairs of bracket arms to be arranged in relatively 70 offset relation. The bracket arms 2 are then bent upwardly at substantially right angles to the shoulders of the base and afford means for permitting clamping arms 6 carrying bearing pintles 7 upon the offset ends thereof with the apertured bracket arms 2, the said pintles 7, obviously, being received in the apertures 3 of the bracket arms. In this connection, it will be noted, that the intermediate portions of each of the clamping 80 arms 6 are bent inwardly or offset as at 8 and provided with curved finger pieces 9 whereby engagement with the clamping arms will be materially facilitated. The clamping arms 6 when swung inwardly are 85 arranged in proximity to the respective shoulder portions 5 of the base 1 and hence, will serve as means for efficiently clamping trousers arranged therebetween, thus, properly supporting the same and serving to retain the original shape thereof.

In order that the hanger may be readily engaged with a suitable support, such as a door, wardrobe or other article of furniture, openings indicated by the numeral 10 may 95 be and preferably are formed in the base 1 at points in proximity to the marginal portions thereof; it being noted in this connection, that the lower marginal portion of the base is flanged as at 11 to permit the same to 100 be properly engaged with a support.

From the foregoing, it will be readily understood that with my improved trouser hanger, I am enabled to support a plurality of pairs of trousers, the same depending 105 from the support in a manner to permit the ready removal of any one pair without disturbing or wrinkling the other pairs. Furthermore, accidental disengagement of the trousers from the clamping arms 6 will be 110

positively prevented due to the manner in which said arms are engaged therewith, these arms, as will be noted, being swung downwardly and then engaged with the adjacent 5 portions of the trouser legs.

Manifestly, the construction shown is capable of considerable modification and such modification as is within the scope of my claims, I consider within the spirit of my 10 invention.

I claim:—

1. A trouser hanger including a base bent throughout its length to provide a plurality of stepped shoulders, brackets positioned adjacent each of the ends of said shoulders, and clamping bars having their opposite ends disposed at substantially right angles pivoted between said brackets and having 15

the intermediate portion thereof offset and formed with a finger piece. 20

2. A trouser hanger including a base bent throughout its length to provide a plurality of stepped shoulders, brackets arranged adjacent each of said shoulders, and clamping means engaged with said brackets. 25

3. A trouser hanger including a base bent throughout its length to provide a plurality of parallel shoulders, said shoulders being arranged in stepped relation, bracket arms formed integral with the opposite ends of 30 the shoulders, and clamping arms pivotally engaged with said bracket arms.

In testimony whereof, I affix my signature hereto.

ROBERT W. VAN BUREN.
